(57) CLAIM

The ornamental design for a box with lid, as shown.

DESCRIPTION

FIG. 1 is a perspective view of a box with lid showing my new design;

FIG. 2 is a front view thereof;

FIG. 3 is a side view thereof;

FIG. 4 is a top view thereof; and,

FIG. 5 is a bottom view thereof.

The broken line showing in FIGS. 1 and 4 is for illustrative purposes only and forms no part of the claimed design.
